(57) **CLAIM**

The ornamental design for a combined pill container and reversible lid, as shown and described.

DESCRIPTION

FIG. 1 is a perspective view of a combined pill container and lid, with the lid in the first of two reversible orientations, showing our new design;

FIG. 2 is a perspective view of a combined pill container and lid, with the lid in the second orientation;

FIG. 3 is a top plan view of the combined pill container and lid of FIG. 2;

FIG. 4 is a right side elevation view of the combined pill container and lid of FIG. 2; and,

FIG. 5 is a front side elevation view of the combined pill container and lid of FIG. 2.

A left side and back side view are not included because these are mirror images of the right side view and front side view respectively.

The bottom is not shown and has no ornamental features.
